Specification for Design.

Patented Dec. 20, 1921.

Application filed February 24, 1921. Serial No. 447,621. Term of patent 14 years.

To all whom it may concern:

Be it known that I, CLAUDE W. SUTTON, a citizen of the United States, and a resident of the city of Wilmington, county of New Castle, State of Delaware, have invented a new, original, and ornamental Design for Waste-Baskets or Similar Article, of which the following is a specification,

reference being had to the accompanying drawing, forming a part thereof.

The figure is a perspective of a waste basket formed of embossed fiber.

I claim:—

The ornamental design for a waste basket or similar article as shown.

CLAUDE W. SUTTON.
